UNITED STATES PATENT OFFICE.

ALIDA M. MARCOUX, OF MILFORD, MASSACHUSETTS, ASSIGNOR TO
DRAPER COMPANY, OF HOPEDALE, MASSACHUSETTS, A CORPO-
RATION OF MAINE.

FILLING-REPLENISHING LOOM.

SPECIFICATION forming part of Letters Patent No. 745,363, dated December 1, 1903.

Application filed September 8, 1903. Serial No. 172,372. (No model.)

To all whom it may concern:

Be it known that I, ALIDA M. MARCOUX, a subject of the King of Great Britain, and a resident of Milford, county of Worcester, State 5 of Massachusetts, have invented an Improvement in Filling-Replenishing Looms, of which the following description, in connection with the accompanying drawings, is a specification, like characters on the drawings representing like parts.

This invention relates more particularly to looms provided with automatic filling-replenishing mechanism—such, for instance, as forms the subject-matter of United States 15 Patent No. 529,940—wherein the shuttle is provided automatically with a fresh supply of filling at the time such replenishment becomes necessary. Sometimes the shuttle mis-threads after such replenishment, and then a 20 second supply of filling is inserted in the shuttle, and ordinarily the threading is then properly effected. As the mistread occasionally happens with the insertion of the second filling-supply, it is desirable to there- 25 upon effect the stoppage of the loom in order that the weaver may ascertain the cause of the trouble and correct it, for otherwise a number of filling changes might be caused, emptying the hopper or filling-feeder.

30 Devices have been provided to stop the loom automatically if the replenishing mechanism is operated a predetermined number of times in succession, one of such devices being shown in United States Patent No. 35 727,014, dated May 5, 1903. In such apparatus the loom is stopped automatically after two successive operations of the replenishing mechanism, a mistread occurring on each operation.

40 My present invention has for its object the simplification and improvement of the means for effecting such automatic stoppage of the loom after a predetermined number of successive operations of the replenishing mech- 45 anism.

The various novel features of my invention will be fully described in the subjoined specification and particularly pointed out in the following claims.

50 Figure 1 is a left-hand side elevation of a

sufficient portion of a filling-replenishing loom to be understood with one embodiment of my invention applied thereto, the shipper being omitted and the knock-off lever being shown in section. Fig. 2 is a top or plan view 55 of the novel part of the apparatus illustrated in Fig. 1, showing the filling-detector and parts controlled thereby in normal position. Fig. 3 is an enlarged detail, in side elevation, of the mechanism shown in Fig. 2, the nearer 60 side of the detector-slide and its guide or stand being broken out; and Fig. 4 is an opposite side elevation of the device which at the proper time actuates the knock-off lever to release the shipper.

The lay A^3 , breast-beam A^{40} , having at one end the usual notched holding-plate N for the shipper S and at the other end supporting the filling-replenishing mechanism, a portion of the filling-feeder F thereof being 70 shown in Fig. 1, the controlling rock-shaft d' , which governs the operation of the filling-replenishing mechanism in well-known manner, and the upturned arm d , fast on said rock-shaft and in the outward path of movement of the detector or fork slide, may be 75 and are all substantially as in said Patent No. 529,940.

The slide f^x , longitudinally movable in a guide f^2 , transversely secured on the breast-beam, supports in usual manner a filling fork or detector f , of usual construction, the fork-tail f^{20} being adapted to coöperate with the hook w of the weft-hammer or actuator W upon failure of the filling to tilt the fork. 80

As is well known to those skilled in the art, if the fork is not tilted on the detecting-pick the slide f^x is moved outward and through the arm d rocks the shaft d' and effects a change of filling. The slide has one 90 side extended forward, as at f^3 , and hooked to engage the upper overturned end of the arm d , as herein shown, and near its outer end the sides of the slide are provided with upturned ears f^4 , which sustain a transverse fulcrum or pivot pin f^5 for a knock-off latch or dog h . (Very clearly illustrated in Figs. 3 and 4.) The latch or dog is made as a rather heavy casting, having near its rear end 95 an elongated slot h^8 , through which the pin 100

f^5 passes, the dog being hung thereon between the ears f^4 and movable longitudinally relatively to the slide, as will be described. The under side of the dog is cut away at one side of its longitudinal center and at its front end to present a series of transverse depressions, three being herein shown and indicated at 1, 2, and 3, Figs. 3 and 4, in a stepped arrangement.

- 10 A coöperating detent, shown as a lug or pin f^{10} , extends inward from the adjacent side of the slide f^X and projects into the cut-away part of the dog, said detent being adapted to enter any one of the depressions referred to. Normally the detent coöperates with the lowest depression 1, the dog then being as far toward the outer end of the slide as it can go (see Fig. 3 and also Fig. 1) and held up in its highest position. On the opposite side the dog has a depending portion h^{10} , its lower edge being cut away to present two downturned shoulders h' h^2 , also arranged in step formation, the inner shoulder h' being lower than shoulder h^2 .
- 25 As shown in Fig. 2, a knock-off lever n n' is fulcrumed at n^X on the breast-beam, to release the shipper from its holding-notch, and, as shown clearly in Figs. 1 and 2, the arm n' normally extends under the dog h , said arm being provided with an upturned lug or abutment n^2 , which is in the outward path of movement of the shoulder h' when the slide f^X is moved out.

With the parts in the position shown in the drawings, let it be supposed that the filling fails and such failure is detected by the detector f . The latter is not tilted, and the slide f^X is moved outward by the weft-hammer, and the extension f^3 acts through arm d to turn 35 the rock-shaft d' and effect filling replenishment. At the same time the outward movement of the slide brings the shoulder h' of the dog into engagement with the abutment n^2 and stops the movement of the dog, the 40 slide continuing to move outward. Such stoppage of the dog disengages the detent f^{10} from the depression 1, and as the slide completes its outward movement said detent will be under the depression 2, so that when the slide 45 moves in the outer end of the dog will drop and the detent will enter the depression 2. This brings the shoulder h^2 into position opposite the abutment n^2 , and if the slide is moved out on the next detecting-pick said 50 abutment will engage the shoulder h^2 and stop the dog, while the slide continues to move out, withdrawing the detent f^{10} from depression 2 and positioning it beneath the third and outermost depression 3. Now the slide 55 moves in, the outer end of the dog drops again, and the detent enters said depression 3, so that the abutment n^2 will be in the path of the outer end h^3 of the part h^{10} of the dog which has been moved inward relatively to 60 the slide as far as it can go, the pin f^5 abutting against the outer end of slot h^X . If a 65 third outward movement of the slide takes

place, the end h^3 and abutment n^2 engage, and as the slide completes its movement the knock-off lever is turned and the shipper is released to stop the loom. Should the shuttle thread properly after the first or second operation of the replenishing mechanism, the weft-hammer will act upon the inner end of the dog to return it to the normal position, (shown in the drawings,) and such resetting of the dog is similarly effected by the weft-hammer when the loom is started after it has been stopped as described.

It will be manifest that the number of parts has been materially reduced in my present invention, and a single member (the dog) effects the actuation of the knock-off lever when the slide has been moved out a predetermined number of times in succession. On the first and second outward movements of the slide the filling-replenishing mechanism is operated, as will be obvious. The horizontal distance between the shoulder h^2 and the outer end h^3 of the part h^{10} of the latch or dog is made longer than the distance between the shoulders h' and h^2 in order to provide for the necessary movement of the knock-off lever on the last outward stroke of the slide f^X .

My invention is not restricted to the precise construction and arrangement shown and described, as the same may be modified or varied by those skilled in the art without departing from the spirit and scope of my invention.

Having fully described my invention, what I claim as new, and desire to secure by Letters Patent, is—

1. In a loom, a filling-detector, its slide adapted to be moved upon detection of filling failure, filling-replenishing mechanism controlled by or through the slide, a shipper, a releasing device therefor, a latch movable with and also longitudinally of the slide, and means to effect operative engagement of said latch and releasing device to actuate the latter upon movement of the slide after a predetermined number of successive operations of the filling-replenishing mechanism.

2. In a loom, a filling-detector, its slide adapted to be moved upon detection of filling failure, filling-replenishing mechanism controlled by or through the slide, a shipper, a releasing device therefor, a latch pivotally mounted on and having a limited longitudinal movement relative to the slide, and means to intermittently effect movement of the latch into operative position by a predetermined number of successive movements of the slide, to actuate the releasing device upon the next movement of the slide.

3. In a loom, a filling-detector, its slide adapted to be moved upon detection of filling failure, filling-replenishing mechanism controlled by or through the slide, a shipper, a releasing device therefor, a latch pivotally mounted on and having a limited longitudinal movement relative to the slide, a series of shoulders on the latch to be engaged suc-

cessively by the releasing device upon successive movements of the slide, to effect relative movement of the latch and the latter, and a detent to maintain the latch in position for each of such engagements.

4. In a loom, a filling-detector, its slide adapted to be moved upon detection of filling failure, filling-replenishing mechanism controlled by or through the slide, a shipper, a releasing device therefor, a latch movable with and also longitudinally of the slide, a detent to cooperate with the latch, and means to change the position of the latch step by step longitudinally of the slide upon a predetermined number of successive movements of the latter, to thereby finally position the said latch to engage and actuate the releasing device upon an immediately-following movement of the slide.
- 20 5. In a loom, a filling-detector, its slide adapted to be moved upon detection of filling failure, filling-replenishing mechanism controlled by or through the slide, a shipper, a releasing device therefor, a latch pivotally mounted on and having a limited longitudinal movement relative to the slide, a series of stepped shoulders on the latch and a corresponding series of depressions, and a detent on the slide to cooperate with one after another of the depressions and permit one shoulder after another to move into operating position, a predetermined number of successive movements of the slide causing the shoulders to successively engage the releasing device and effect movement of the latch relatively to the slide until the last one of the movements of the latter, such final movement of the slide acting through the latch to actuate the releasing device.
- 35 6. In a loom, a filling-detector, its slide adapted to be moved upon detection of filling failure, filling-replenishing mechanism controlled by or through the slide, a shipper, a knock-off lever therefor, a latch fulcrumed upon and also having a limited longitudinal movement relative to the slide and provided with two shoulders, and a detent to govern the angular movement of the latch, two successive movements of the slide causing successive engagement of the knock-off lever with the shoulders, to move the latch into operative position, a third movement of the slide moving the latch therewith and causing its end to engage and actuate the knock-off lever to release the shipper.
- 40 7. In a loom, a filling-detector, its slide adapted to be moved upon detection of filling failure, filling-replenishing mechanism con-

trolled by or through the slide, a shipper, a knock-off lever therefor, a latch having a longitudinal slot, and a plurality of shoulders on its lower edge, a fulcrum-pin extended through the slot and fixed upon the slide, and a detent on the latter to control the angular position of the latch and normally retain it 60 inoperative, a plurality of successive movements of the slide causing successive engagement of the knock-off lever and the latch-shoulders to change the position of the latch the length of the slot and position its outer 70 end behind said lever, an immediately-following movement of the slide causing the end of the latch to engage and actuate the knock-off lever.

8. In a loom, a filling-detector, its slide, an actuator to move the latter upon detection of filling failure, filling-replenishing mechanism controlled by or through the slide, a latch angularly and longitudinally movable relatively to the slide and mounted thereon, a detent 80 to govern the angular position of and normally maintain said latch inoperative, a plurality of stepped shoulders on the latch, a shipper, and a releasing device therefor in the path of and adapted to engage the shoulders 85 successively upon a predetermined number of successive movements of the slide, to thereby effect relative movement of the latch and slide and operatively position the end of the latch, another and immediately-following 90 movement of the slide causing the latch to move in unison therewith and actuate the releasing device.

9. In a loom, a filling-detector, its slide, an actuator to move the latter upon detection of filling failure, filling-replenishing mechanism controlled by or through the slide, a latch mounted on and capable of a limited amount of lost motion relatively to the slide, a detent to normally maintain said latch inoperative, 100 a shipper, and a releasing device therefor, a predetermined number of successive movements of said slide effecting successive engagements of the latch and releasing device to take up the lost motion of the latch and 105 operatively position the same, an immediately-following movement of the slide moving the latch in unison therewith to engage and actuate the releasing device.

In testimony whereof I have signed my name to this specification in the presence of two subscribing witnesses.

ALIDA M. MARCOUX.
